UNITED STATES PATENT OFFICE.

GEORGE W. COVINGTON, OF EMERYVILLE, CALIFORNIA.

JOCKEY'S GRIP OR HANDHOLD.

SPECIFICATION forming part of Letters Patent No. 747,145, dated December 15, 1903.

Application filed December 13, 1901. Serial No. 85,798. (No model.)

To all whom it may concern:

Be it known that I, GEORGE WASHINGTON COVINGTON, a citizen of the United States, residing at Emeryville, in the county of Alameda and State of California, have invented certain new and useful Improvements in Jockeys' Grips or Handholds, of which the following is a specification.

This invention is a simple and convenient implement adapted to be used in connection with bridle-reins or driving-reins in order to insure a good hand-grip in pulling. It is particularly adapted for the use of jockeys in racing, where a reliable grip of this character eases the hands and takes off a great part of the strain now required in restraining a horse. Jockeys at present knot the bridle-reins together and make a kind of a pulling-grip; but since the reins are not widely enough separated the hand is cramped between them and the fingers have not full power in the pull. My implement gives such a firm and reliable grip.

My invention also comprises a device for permitting the hands to rest upon the horse's neck without gripping the reins with the fingers and without any liability of the reins slipping through the hand.

The invention is fully hereinafter described, and is shown in the accompanying drawings, in which—

Figure 1 is a plan view of the grip or handhold detached from the reins. Fig. 2 is a similar view, but with the reins connected or cinched in the grip. Fig. 3 is an edge view partly broken away and showing the auxiliary loop.

The grip or handhold A is a bar composed of a single piece of some suitable material. I prefer to use aluminium on account of its lightness; but other metals or materials can be used instead. In shape it preferably somewhat tapers or is rounded inwardly from both ends toward the middle, as illustrated fully in Fig. 1, and it will be noted that all edges are rounded, as shown at a b, so as to leave no corners, angles, or ridges to injure the hand or make an uncomfortable grip. Near each end of the bar is an opening c, which I prefer to make of the approximately semicircular shape shown. On one edge is formed a concave projection d, with rounded corners,

which acts as a double stop to keep the two reins from working toward each other.

The reins B B are cinched through and around the grip, as shown in Fig. 2. The end 55 of one rein is passed back through each end of the slots in the bar, then brought under to the front, and then over and back and through the loop. This forms a cinch which tightens with the pull and which cannot slip. 60 The inner edges of the reins can work in as far as the stop will permit, but no farther, and hence the reins remain separated, so that the hand, with either an overhold or underhold, has a comfortable grip and can exert 65 its utmost power without being cramped by the reins. No buckles or movable or adjustable parts are employed, and the bar being made in one piece of sufficient strength is practically indestructible. 70

In connection with this device, but with more special reference to bridle-reins, I attach to the side of the bar a loop C, usually of leather, and I prefer to rivet the loop firmly in place and for the purpose provide the rivet-holes e. Riding at ease or when the horse is not under a strong pull the jockey often finds relief in resting his hands on the horse's neck or withers. This rest is not complete if he is obliged to maintain a grip on the reins. When 80 this loop is attached to the hand-grip, the thumbs can be passed upwardly through it, the reins being released. Then both hands can rest upon the horse, the thumbs pulling a little sidewise against each other and giving great relief to the hands. In this position, although the rider loosens his grip on the reins, he does not lose control of the horse, and the change to the gripping position can be made instantly. 85 90

A special advantage of my grip is that as the rider's fingers are not cramped he is not obliged to change holds on the reins, as is now the case, and the horse is not fretted or made nervous or angry, as he frequently is 95 when the hold is repeatedly changed.

Although specially adapted for bridle-reins, the efficacy of my device as a pulling-grip for driving-reins is obvious.

By reason of the tapered form of the bar it 100 will be noticed that the upper and lower edges diverge near the ends of the bar. These di-

vergent edges afford bearings for the reins to allow the same to firmly grip the bar and allow the loops of the cinch to assume the most effective position for a tight hold. The bar 5 is in the form of a flat plate.

Having thus fully described my invention, what I claim as new, and desire to secure by Letters Patent, is—

1. A grip-bar having openings extending 10 therethrough near the ends, the ends of the bar being wider than the central portion thereof to provide divergent inclined edges, substantially as described.

2. A grip-bar having openings extending 15 transversely through the bar near the ends, and stop means located between the adjacent edges of the wrapped portion of the reins, said bar with its attached stop means being adapted to be held in the hand, substantially 20 as described.

3. A grip-bar comprising a flat plate with openings at or near its ends extending through from the front to the rear face of the plate and stop means projecting from the edge of the plate, substantially as described. 25

4. In combination, a flat bar having openings extending therethrough at its ends from one flat face to the other and reins passing through said openings and wrapped about the ends of the bar, said bar having stop means 30 intermediate the adjacent edges of the reins, substantially as described.

In testimony whereof I have affixed my signature, in presence of two witnesses, this 4th day of December, 1901.

GEORGE W. COVINGTON.
